UNITED STATES PATENT OFFICE

GUY E. RIEGEL, OF SPOKANE, WASHINGTON, ASSIGNOR TO AUTOMATIC RADIO CORPORATION, OF SPOKANE, WASHINGTON, A CORPORATION

CHECK CONTROLLED APPARATUS

Application filed June 5, 1930. Serial No. 459,336.

My present invention relates to improvements in check controlled apparatus of the type employing a check or coin operated electric switch that is normally open, but is closed for a predetermined time, the switch being mechanically controlled by coin operating mechanism. While my check or coin controlled apparatus is applicable for various uses, it is particularly designed for predetermining the time of operating a radio receiving set, and the prime mover for the apparatus and radio instrument is preferably an electrically operated clock. The electrical clock is continuously operating, without necessity for winding, and is therefore available for use in operating the radio set under control of the coin operating mechanism.

In carrying out my invention the electric clock and the radio receiving set are preferably combined in a cabinet or fixture that may be used in a hotel room, (or other suitable place) and the radio instrument receives its required electricity from the wires of the electrical clock. By dropping a coin in a slot 25 of the cabinet, the hotel guest is permitted to avail himself of the entertainment from the radio set for a predetermined time, and at the end of the predetermined period of time the radio instrument is automatically rendered 30 inoperative but is re-set for a succeeding operation.

A continually revolving shaft of the clock is employed as the prime mover for mechanically operating or rotating a coin carrier, and the duration of the operating-time 35 of this coin carrier is governed or controlled by the radio switch. In the absence of a check or coin the radio-switch remains open and the coin control mechanism or apparatus 40 remains stationary.

The invention consists in certain novel combinations and arrangements of parts as will hereinafter be more fully set forth and claimed. In the accompanying drawings I 45 have illustrated one complete example of the physical embodiment of my invention wherein the parts are combined and arranged according to one mode I have thus far devised for the successful application of the principles of my invention. It will, however, be

understood that various changes and alterations may be made in the exemplified structure, within the scope of my claims, without departing from the principles of my invention.

Figure 1 is a perspective view of a cabinet or article of furniture in which the electrical clock and the radio receiving set are embodied, together with the control mechanism of my invention.

Figure 2 is a diagrammatic view of the electrical wiring for the clock and the radio receiving set or instrument.

Figure 3 is an enlarged view in elevation of the coin control mechanism and time switch, the initial position of the coin carrier being indicated by full lines and the end of the movement of the carrier being indicated by dotted line position.

Figure 4 is a detail view of part of the coin carrier in an intermediate position and while being operated by the clock-movement.

Figure 5 is a top plan view showing the assembly of the clock and the coin controlled mechanism.

Figure 6 is a perspective view of there setting, bell crank, lever, and Figure 7 is a similar view of the switch lever.

In Figure 1 where the general embodiment of my invention is exemplified I employ a cabinet or box 1 of suitable size and shape having the electrical clock 2 appearing in its front face, and within the cabinet is located the radio receiving set or instrument indicated by dotted lines at 3, and with the control knobs or handles 4 in positions for use by the operator of the set.

The loud speaker for the receiving instrument is designated 5, and is located just below the dial or face of the clock 2.

In Figure 2 the electric current for the clock includes the wires 6 and 7, and the radio circuit includes wires 8 and 9 that are connected as indicated with the wires 6 and 7 of the clock. The clock is assumed to be operating at all times, but the radio instrument is operated only when the switch 10 in the radio circuit is closed. The switch 10 is shown open in Figure 2, but it is automatically closed when a coin, as C (dotted lines

Figures 3 and 4) is employed for performing its functions. In the diagram of Figure 2, the antennæ of the radio instrument is indicated at 11 and the ground wire is designated 12.

5 The coin C is inserted in the slot 13 in the upper part of the cabinet and passes down through a coin chute 14 within the cabinet. By means of the coin carrier 21 (as will be described) the coin is carried or transferred from chute 14 to the spaced, vertically arranged, discharge chute 15, and finally passes out through the slide 16 to a suitable receptacle, or collection box.

15 For the operation of the coin carrier I utilize a continuously revolving shaft 17 of the clock, and place thereon the motor wheel 18 with its peripheral teeth 19, it being understood that the motor wheel revolves clockwise 20 at all times with the shaft 17.

A frame 20 is provided for the support of some of the operating parts and arranged within the cabinet, back of the clock 2.

25 The coin carrier 21 is a section of the chute complementary to the chutes 14 and 15, and is provided with a hub 22 loose on the shaft 17. Due to the weight of its lower end, the carrier 21, by gravity is returned to the perpendicular position of Figure 3, and because 30 of the rounded upper end 23 of the carrier co-acting with the complementary lower end of chute 14, the carrier is prevented from turning anti-clockwise to an excessive degree. As indicated by full lines and dotted lines in 35 Figure 3 the coin carrier is permitted to swing on its axial center, with the shaft 17, from the full line vertical position, to the dotted line horizontal position. The rounded, discharge end 23 of the carrier however 40 swings downwardly and to the right a sufficient distance to insure that the coin C will roll by gravity from the discharge end 23 into an edge-slot 24 of the discharge chute 15, and the coin is thus passed to the collection box.

45 The carrier is actuated by the wheel 18 and is coupled therewith for its movement by means of a lever and ratchet device carried on an extension 25, of one wall of the carrier, that projects below the open lower end of the carrier.

50 A pawl 26 having a ratchet-head 27, for engagement with the ratchet teeth of the wheel 18, is pivoted at 28 on the extension, and the pawl or ratchet lever 26 has an extended arm 29 with a lobe 30 on one of its edges. The ratchet lever is positioned so that its pawl 27 may engage the ratchet wheel, and at the same time the lobe protrudes in the open end of the carrier to form a closed 55 bottom of the carrier to support a coin therein.

55 On the underside of the ratchet lever adjacent its hub portion are provided two spaced lugs 31 and 32 with which a spring detent 33 co-acts through a lug 34 on the detent. 60 The lug 34 on the detent co-acts with tooth

32 to hold the ratchet lever in full line position of Figure 3 where the switch 10 is open.

The ratchet lever is dislodged from its full line position of Figure 3 by the weight of the coin as it falls through the perpendicular carrier and strikes against the lobe 30 that is projecting into the open end of the carrier. The impact of the coin depresses arm 29 and raises lever arm 26 and the tooth 32 is "snapped" over the lug 34 to the left side of the tooth, as in Figure 4, where the ratchet lever is held in engagement with the ratchet wheel, and the lobe 30 of the lever arm prevents the coin C from falling through the open end of the carrier.

65 It will be remembered that the ratchet wheel 18 is continuously revolving (intermittently under its electrical operation with the clock 2) and therefore, when the ratchet lever engages the rack wheel, the carrier is coupled with the wheel and the former moves with the latter until it reaches a position approximating the dotted line position of Figure 3.

70 When the carrier attains the position for discharging its coin C to the slot 24 of the discharge chute 15, the carrier is automatically released from its coupled relation to the ratchet wheel, through the instrumentality of a release, bell crank lever having the two 75 arms 35 and 36 and pivoted at 37 on the extension plate 25 with arm 36 in proximity to the tooth 31 of the ratchet lever.

75 The long arm 35 of the bell crank lever moves in an arcuate path beyond the periphery of the ratchet wheel, and in this path is located a release pin as 38. The pin may be set in a selected one of an annular series of pin holes 39 in the bracket or frame 20, or in a special plate provided therefor and attached to the bracket.

80 The location of the pin 38 in a selected hole 39 determines the length of travel of the carrier and also determines the length of the period during which the circuit maker or switch 10 is closed and the radio set is operating.

85 With the carrier turning clockwise in Figure 3 and the parts as indicated in Figure 4, when the long arm 35 strikes pin 38 the release bell crank lever is swung on its pivot 37 and the short arm 36 bearing against tooth 31 swings the ratchet lever from engagement with the toothed ratchet wheel 18. Then the carrier, by gravity swings anti-clockwise on its shaft 17 back to position of full lines in Figure 3, opens the closed switch 10, and the spring detent 34 engages the opposite side of the tooth 32 to hold the ratchet lever in position to hold open the circuit maker or switch 10.

90 The carrier is thus released by the use of the bell crank lever, and the switch 10 is reset by the use of the gravity-swinging car- 130

rier and its re-setting spring detent and ratchet lever.

The switch or circuit maker is mounted on a plate 40 that is secured to the frame 20 and the plate is located in proximity to the lower edge of the ratchet wheel for co-action with the ratchet lever. Terminals 41 and 42 of the wire 9 are secured at the opposite ends of the plate, and a stationary contact member or blade 43 is used with the resilient or spring, movable blade 44 of the switch. On the upper side of the spring blade is fixed a lug or abutment 45, and beneath the spring blade and fixed to the plate 40 is a stop lug or boss 46.

As shown, the spring blade of the switch is approximately tangential to the ratchet edge of the wheel 18, and the outer end of the ratchet lever is adapted to ride up the inclined face of the spring blade and depress the blade to remove it from electrical contact with the stationary blade 43. The stop boss or pin 46 prevents excessive depression of the spring blade, and the ratchet head 27 contacts with the lug 45 at the same time the spring blade contacts with the boss 46. The ratchet lever thus holds open the switch or circuit maker 10, and of course, when the circuit maker is opened the radio circuit is broken and the radio set ceases to operate.

The carrier is thus returned, by gravity, to its perpendicular position, with the opening 23 registering with the lower open end of the receiving chute 14, as indicated in Figure 3 and the mechanism is again set for a succeeding operation when a coin is dropped into the coin slot and passes through the chute.

Having thus fully described my invention, what I claim as new and desire to secure by Letters Patent is:—

1. The combination with a circuit maker, means for closing the circuit and a rotary operating member, of a coin carrier loosely associated with the member and adapted to rotate therewith, means for coupling the carrier with said member, means for releasing the carrier from the member, and means on the circuit maker for coaction with the coupling device for opening the circuit maker.

2. The combination with a circuit maker, means for closing the circuit maker and a rotary member, of a coin carrier loosely associated with the member and adapted to rotate therewith, a coupling device carried by the carrier, means on the member for co-action with said device, releasing means on the carrier for the coupling device, means in the path of the releasing means for actuating the latter, and means on the circuit maker for co-action with the coupling device for opening the circuit maker.

3. The combination in a coin controlled apparatus with a pair of spaced, related coin chutes, of a rotary coin carrier adapted to

receive the coin from one and deliver it to the other chute, a rotary operating member, means for coupling the carrier with said member, means for disconnecting said carrier from the member, a circuit maker and closing means therefore, and means on the circuit maker for co-action with the coupling means for opening the circuit maker.

4. The combination in a coin controlled apparatus with a pair of spaced chutes and an intermediate rotary, transfer chute-carrier, of a rotary operating member, means mounted on the carrier and co-acting means on the member for coupling the member to the carrier, means for releasing the carrier from the member, a circuit closer and closing means therefor, and means on the circuit maker for co-action with the coupling means for opening the circuit maker.

5. In a coin controlled apparatus, the combination with a ratchet wheel and its operating means, of a loosely associated coin carrier, a ratchet mechanism mounted on the carrier and means for engaging the mechanism with the wheel under weight of a coin, means for disengaging said ratchet mechanism, an automatically closed circuit maker, and means on the circuit maker for co-action with the ratchet mechanism for opening the circuit maker.

6. The combination with a shaft and its ratchet wheel, of a coin carrier loosely mounted on the shaft, a weight operated ratchet lever mounted on the carrier for engagement with the wheel, a retaining detent for said lever, a release lever mounted on the carrier, means for actuating the release lever, an automatically closed circuit maker, and an abutment on the circuit maker for co-action with the ratchet lever for opening the circuit maker.

7. The combination with the movable and stationary blades of a circuit maker, of an oscillatable coin carrier and rotating means therefor, coupling means between the rotating means and carrier, said coupling means including a lever on the carrier and an abutment on the movable blade adapted to hold the circuit maker, a weight operated arm on the lever whereby the lever is withdrawn from the abutment of the open circuit maker, and means for uncoupling the rotating means and carrier.

8. The combination with a rotating shaft and its ratchet wheel, of a gravity-returned coin carrier loose on the shaft, a coin-operated ratchet lever mounted on the carrier, a spring detent for said lever mounted on the carrier, a bell-crank release lever mounted on the carrier for co-action with the ratchet lever, a stationary pin in the path of said bell-crank lever, an automatically closed circuit maker, and an abutment on the circuit maker for co-action with the ratchet lever for opening the circuit maker.

9. In a radio receiving instrument, a coin controlled apparatus comprising a clock as a continuously operating motor, an automatically closed circuit maker for the instrument, a rotary coin carrier and means for coupling said carrier with the motor, means for releasing the coupling between the carrier and the motor, means for returning the coin carrier to normal position when the coupling is released, and means on the circuit maker for co-action with the coupling means whereby the circuit maker is opened when the coupling is released.

10. In a radio receiving instrument, a coin controlled apparatus comprising a clock as a continuously operating motor, a pair of spaced coin chutes, a gravity actuated carrier between the chutes, means for coupling the carrier to said motor, means for releasing the coupling between the carrier and motor, an automatically closed circuit maker, and means on the circuit maker for co-action with the coupling means whereby the circuit maker is opened when the coupling is released.

In testimony whereof I affix my signature.
GUY E. RIEGEL.
